ATTORNEY

UNITED STATES PATENT OFFICE.

JOSEPH KAUFMANN, OF NEW YORK, N. Y.

DESIGN FOR A CIGAR LIGHTER AND CUTTER STAND.

SPECIFICATION forming part of Design No. 18,421, dated July 3, 1888.

Application filed April 17, 1888. Serial No. 270,960. Term of patent 3½ years.

To all whom it may concern:

Be it known that I, JOSEPH KAUFMANN, of New York, in the county and State of New York, have invented and produced a new and original Design for a Cigar Lighter and Cutter Stand, of which the following is a specification, reference being had to the accompanying illustration, forming part thereof.

The leading features of my design are conventional representations of the column or post, lantern, and burner of street-lamp posts; also, in connection therewith, representations of posts and chains rising from the base of the posts on one side only thereof; also, and as a principal feature of the design and giving its character, there is a representation of a man having his boots polished by a boot-black. The man stands with his back to the post, one foot resting on the cutter-box, which is a conventional representation of the box carried by boot-blacks. In one hand is a cane carried under the arm, and in the other a cigar. The boot-black is represented kneeling in the act of plying his brushes. In the side of the box

is a hole, and the cutter-blade is represented partly in dotted lines.

In the accompanying illustration, A is the column or post that represents a lamp-post; B, the lantern; D, the figure of a man representing a fashionably-attired dude; E, the boot-black; F, the box provided with a hole, *h*, and cutter-blade *i*.

G represents the posts, H the chains, and I the base, which is of circular form, supporting the foregoing elements of the design. 35

I claim—

The design for a cigar lighter and cutter stand herein described and shown, the same being a conventional representation of a lamp-post and boot-black's box, and consisting of 40 the post A, lantern B, figure of a man, D, figure of a boot-black, E, box F, posts G, chains H, and base I.

JOSEPH KAUFMANN.
